FURNACE WALL CONSTRUCTION

Louis H. Hosbein, Glencoe, Ill., assignor to M. H. Detrick Company, Chicago, Ill., a corporation of Delaware

Original application October 18, 1939, Serial No. 300,020. Divided and this application July 29, 1941, Serial No. 404,551.

9 Claims. (Cl. 72—101)

This invention relates in general to furnace wall construction and has more particular reference to refractory blocks or tiles for the construction thereof. The instant application is a division of my co-pending application Serial No. 300,020, filed October 18, 1939, which has now issued as Patent No. 2,279,515, granted April 14, 1942.

The invention is shown herein as embodied in one of the furnace walls disclosed and described in my co-pending application aforesaid, but it will be understood that this is presented merely for illustrative purposes and is not necessarily restricted thereto, and it will be apparent that the invention may be embodied in various other forms of wall structures having other and more general valuable application.

A principal object of the invention is the provision of a refractory block or tile so formed that but a single form of tile is required for the construction of an entire furnace wall.

Another important object of the invention is the provision of a relatively thin refractory tile, which will be effective to minimize air or gas leakage through the wall.

A further important object of the invention is the provision of such a refractory block or tile which is simple, inexpensive and easily and economically manufactured.

Numerous other objects and advantages of the invention will be apparent as it is better understood from the following description, which, when taken in connection with the accompanying drawing, discloses a preferred embodiment thereof.

In the drawing.

Figure 1 is a perspective view of the refractory block or tile, taken from the top and rear thereof;

Fig. 2 is a perspective view of the refractory block or tile, taken from the bottom and rear thereof; and

Fig. 3 is a transverse, vertical sectional view of a wall in which the tile are embodied.

Referring more particularly to Fig. 3 of the drawing, reference numeral 11 indicates a vertically disposed frame member, a plurality of which are provided in spaced relationship longitudinally from each other in the direction of the wall, as more particularly disclosed in my said co-pending application. A plurality of horizontally disposed frame or supporting members 12 are secured by means of bolts 13 to the vertical frame members 11 to provide a skeleton frame for the wall having any suitable or desired

type of foundation therefor. The frame members 11 may be of any suitable shape, while the horizontal frame members 12 are provided with longitudinally extending recesses 14 in their inner surfaces (Fig. 3) and longitudinally extending marginal recesses 15 and 16 along the upper and lower edges of their rear surfaces. The recess or channel 14 is positioned a short distance below the horizontal center line of each 10 of the frame members 12, and the latter are preferably provided with a plurality of elongated apertures 17 extending therethrough substantially on the center line thereof. The apertures 17 are spaced longitudinally of the members 12 15 for the purpose of accommodating the bolts 13 and for another purpose to be later more fully described.

The inner surface of the instant furnace wall (to the right in Fig. 3) comprises a plurality of 20 refractory blocks or tiles, indicated generally by reference numeral 18. Referring more particularly to Figs. 1 and 2, each of the blocks or tiles 18 is in the shape of a parallelepiped having front and rear surfaces 19 and 21, respectively, 25 top and bottom side surfaces 22 and 23, respectively, and right and left end surfaces 24 and 25, respectively. It will be understood that the refractory tile 18 is being viewed from the rear in Figs. 1 and 2. The top surface 22 is provided with a longitudinal groove 26 disposed adjacent the rear surface 21, and the lower surface 23 is provided with a similar groove which comprises three separated portions 27, 28 and 29. The grooves 27, 28 and 29 are in longitudinal alignment with each other and in vertical alignment with the groove 26. The rear surface 21 of the tile is cut away at its lower edge as indicated at 31, 32 and 33 to provide access to the grooves 27, 28 and 29, respectively, from 35 the rear of the block. The upper surface 22 of the tile 18 is provided with a longitudinal seat or shallow groove 34 extending parallel to the groove 26 adjacent the front surface 19. The seat or groove 34 is in vertical alignment with a seat or shallow groove 35 extending in communication therewith along the left hand end 25 of the tile. (Viewing Fig. 2.) The seats or grooves 34 and 35 are appreciably more shallow than the grooves 26 to 29, and are preferably 40 formed with beveled sides, as seen in Figs. 1 and 2. The right hand end 24 of the tile (to the left in Fig. 1) is provided with a projection or tongue 36 which is in vertical alignment with the grooves 34, 35 and extends outwardly from the 45 end surface a distance substantially equal to the

depth of the latter grooves. The bottom surface 23 is provided with a similar projection or tongue 37, as shown in Figs. 2 and 3. The projections or tongues 36 and 37 are preferably formed with beveled sides which conform to the beveled sides of said seats or grooves 34 and 35, and are adapted to be received and seat within said grooves 34, 35, as shown in Fig. 3.

When the refractory tiles 18 are laid in the manner shown in Fig. 3 to form the inner portion of the wall, the blocks of adjacent horizontally disposed rows are positioned in staggered relationship relative to each other, with the projections or tongues 37 of one row of blocks engaging within the grooves 34 of the blocks of adjacent rows, and the projections or tongues 36 and grooves 35 engaging with the respective grooves and tongues of the adjacent blocks of the same row. With this arrangement, the joints between the tiles 18 extending from the front to the rear thereof will be in broken lines instead of straight lines to prevent leakage transversely through the wall, and each of the separate tiles will aid in maintaining the ones adjacent thereto in proper alignment.

Means are shown for sectionally supporting the several refractory tiles 18 and for facilitating the erection and removal and replacement thereof from the rear of the wall. Removably mounted upon the several horizontally disposed frame or supporting members 12 are a plurality of main refractory supporting hanger members, indicated generally by reference numeral 41. As will be seen in Fig. 3, each of the hanger members 41 comprises a main body portion which is disposed transversely of the wall and terminates at the rear adjacent the upper end thereof in a downwardly extending hook member 42. The rear edge of the hanger member 41 is cut away at 43 adjacent and extending below the hook 42, and terminates at its lower end in a rearwardly extending pad 44. With such configuration, the hanger member 41 is adapted to be removably mounted upon a horizontal frame member 12 with the hook 42 engaging within the upper channel or groove 15, the cut-away portion 43 providing clearance for the upper part of the frame member 12, and the pad 44 resting against the forward surface of the frame members. At its forward end, the hanger member 41 is provided with a forwardly extending flange 45 which terminates in upwardly extending, longitudinally spaced lugs 46. As more particularly disclosed in my co-pending application, hereinbefore referred to, each of the hanger members 41 is adapted to support a plurality of refractory tiles 18, eight in number for example, although engaging only the lowermost one of this group of tiles. Such engagement is had only between the cut-away portion 32 of the tile and the flange 45 of the hanger member, and between the lugs 46 and the groove 28 (Fig. 3), if the hanger 41 is positioned to engage the central part of the lowermost tile 18. It is preferred, however, that the end portions of two adjacent tiles in the same row be engaged and supported by the hanger 41, as shown in the drawing. When the tiles are so laid, engagement is had only between the flange 45 of the hanger member 41 and the end cut-away portions 31, 33 of adjacent tiles, and between the lugs 46 and the end grooves 27, 29. The flange 45 thus functions to provide the necessary vertical support for the associated group of refractory tiles 18, the weight of the latter being transmitted to the associated horizontal

frame member 12 by the hook 42 and pad 44 of the hanger 41.

Means are provided, as more particularly described in said co-pending application, for retaining the remaining tiles 18 of the group or section supported by the hanger 41 in proper vertical alignment to prevent inward bulging of the wall. An auxiliary hanger member, indicated generally by reference numeral 51, is provided for each section of refractories 18 supported by a hanger member 41. Each of the auxiliary hanger members 51 comprises an elongated channel member having a pair of outwardly extending, parallel flanges 53, and a hook member 54 extending upwardly therefrom and formed integrally therewith. The upper and lower ends of the body portion 52 terminate in transversely spaced, forwardly extending pads 55.

An auxiliary hanger member 51 is removably mounted upon a horizontal frame member 12 in vertical alignment with each of the main hanger members 41. The upper end of the hook member 54 of the auxiliary hanger 51 engages within the groove 14 in the forward surface of the horizontal frame member 12, with the upper pair of pads 55 being disposed within the lower marginal groove 16 in the rear surface of the frame member. The lower pair of pads 55 engages within the upper marginal groove 15 of the next lower horizontal frame member 12 and on either side of the hook 42 of the next lower main hanger member 41. A plurality of cross pieces 56 are disposed in suitable recesses provided in the flanges 53 of the auxiliary hanger member 51 and are rigidly secured thereto in any desired manner. The cross pieces 56 are vertically spaced from each other a distance equal to twice the height of the refractory tiles 18.

A horizontally disposed retaining member, indicated generally by reference numeral 61, is adapted to be mounted upon each of the cross pieces 56. Each of the retaining members 61 (Fig. 3) terminates at its rear end in a downwardly extending flange portion 62 which engages behind the associated cross piece 56, the main body portion of the retaining member 61 extending between the flanges 53 of the auxiliary hanger member 51. The forward end of the retaining member 61 comprises a horizontally disposed shelf 63 which terminates at its outer end in spaced, vertically disposed flanges 64 extending above and below the shelf 63. The retaining member 61 is of such length that the rear surfaces of the flanges 64 will engage the rear surfaces of the grooves 26 and 28 in the associated refractory tiles 18, when properly mounted as shown in Fig. 3, to prevent forward bulging of the wall. Since the upper flanges 64 will engage the central groove 28 in the lower surface of one tile 18 and the lower flanges 64 will engage the end portions of the grooves 26 in the upper surfaces of the two tiles in the next lower row, it is not essential to have a retaining member 61 disposed between the next two lower rows of refractories. In other words, it is only necessary to employ retaining members in the joints between every other row of tiles, as shown in said co-pending application. It will be seen that the central cut-away portions 32 of the tiles 18 provide clearance for the shelves 63 of the retaining members 61.

Since the main hanger member 41 is entirely unconnected with the refractory tile or tiles 18 directly below it, it is necessary that the retaining members 61 be so spaced vertically, that the

upper one associated with the auxiliary hanger member 51 is disposed between the two upper tiles of a particular section or group. With an even number of tiles in each vertically disposed section or group, the lower retaining member 61 associated therewith will be disposed between the two lower tiles of the section, as shown at the top of Fig. 2. In order to reduce the weight of the auxiliary hanger member 51, the flanges 53 are cut away adjacent the lower end thereof, and the lower retaining member 61 is supported and held against forward transverse movement by the main hanger member 41. This is accomplished by providing a rearwardly extending shoulder 65 at the upper end of the main hanger member 41 (Fig. 3). The shoulder 65 is disposed in vertical alignment with the cross pieces 56, and the rear flange 62 of the associated member 61 engages this shoulder in the same manner as the other members 61 engage the cross pieces 56.

This arrangement has the additional advantage of enabling two upper rows of tiles 18 to be added to the top of the wall with the use of only one member 41 and one member 61 per section or group of tiles, while eliminating the necessity of employing an additional auxiliary hanger member 51. The wall may thus be built up above the top horizontal frame or supporting member 12 so as to afford complete protection for the latter. In order to provide for vertical expansion of the wall, a suitable high temperature resistant material is interposed between the lower tiles of each section or group and the upper tiles of the next lower section, to provide an expansion joint 66 (Fig. 3). This material will completely fill the adjacent grooves in the tiles and entirely cover the forward end of the main hanger members 41.

After all of the refractory tiles 18 have been laid to provide the inner portion of the wall, in the manner above described, the space between the rear surfaces 21 of the tile and the forward surfaces of the horizontal frame members 12 is substantially filled with blocks of any suitable heat resistant or insulation material. The spaces between the insulation blocks and all spaces extending rearwardly from the front surfaces of the horizontal frame members 12 and the auxiliary hanger members 51 are then filled with a suitable plastic insulation material 68.

A plurality of vertically extending plates are then mounted at the rear of the wall to provide an outer casing therefor. The plates may be of substantially the same width as the insulation blocks. In order to rigidly retain the casing plates in position, the auxiliary hanger members 51 are provided with a plurality of vertically spaced, rectangular apertures 71 centrally disposed in the main body portion 52 thereof, and a bolt 72 is adapted to be inserted into each of the apertures 71 from the rear of the wall.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A tile for furnace construction, comprising a refractory block having oppositely disposed front and rear faces and oppositely disposed side

faces, one of said side faces having a plurality of recesses therein communicating with said rear face, said recesses being arranged in spaced relation and extending substantially parallel with said rear face, each of said recesses communicating with a groove spaced from said rear face, the opposite side face having a groove therein extending along said face adjacent to and parallel with said rear face and in line with said first mentioned groove, said grooves being capable of interlocking cooperation with supporting or retaining members.

5 2. A tile for furnace construction, comprising a refractory block having oppositely disposed front and rear faces and oppositely disposed side faces and oppositely disposed end faces one of said side faces having a plurality of recesses therein communicating with said rear face, said recesses being arranged in spaced relation and extending substantially parallel with said rear face, each of said recesses communicating with a groove spaced from said rear face, the recesses at each end of the block communicating respectively with said end faces, the opposite side face having a longitudinally extending groove therein in line with said first mentioned groove, said grooves being capable of interlocking cooperation with supporting or retaining members.

15 3. A tile for furnace construction, comprising a refractory block having oppositely disposed front and rear faces and oppositely disposed side faces, one of said side faces having a plurality of recesses therein communicating with said rear face, said recesses being arranged in spaced relation and extending substantially parallel with said rear face, said side face having cut-away portions extending inwardly of said recesses to form extensions thereof, said cut-away portions being spaced from the rear face of said block, the opposite side face having a groove therein extending along said face adjacent to and parallel with said rear face and in line with said cut-away portions, said cut-away portions and said groove being capable of interlocking cooperation with supporting or retaining members.

25 4. A tile for furnace construction, comprising a refractory block substantially parallelepiped in form and having oppositely disposed front and rear faces and oppositely disposed side faces and oppositely disposed end faces, one of said side faces having a plurality of recesses therein communicating with said rear face and arranged in spaced formation substantially parallel with said rear face, the end recesses of such formation communicating respectively with said end faces, each of said recesses communicating with a groove spaced from said rear face, said groove being capable of interlocking cooperation with a supporting or retaining member.

30 5. A tile for furnace construction, comprising a refractory block substantially parallelepiped in form and having oppositely disposed front and rear faces, oppositely disposed side faces, and oppositely disposed end faces, one of said side faces having a plurality of recesses therein communicating with said rear face and arranged in spaced formation extending substantially parallel with said rear face, the end recesses of such formation communicating respectively with said end faces, each of said recesses communicating with a groove spaced from said rear face, said groove being capable of interlocking cooperation with a supporting or retaining member, and tongue-and-groove means circumscribing said block around its side and end faces and dis-

posed between said recesses and said front face.

6. A tile for furnace construction, comprising a refractory block substantially parallelepiped in form and having oppositely disposed front and rear faces, oppositely disposed side faces, and oppositely disposed end faces, one of said side faces having a plurality of recesses therein communicating with said rear face and arranged in spaced formation extending substantially parallel with said rear face, the end recesses of such formation communicating respectively with said end faces, each of said recesses communicating with a groove spaced from said rear face, said groove being capable of interlocking cooperation with a supporting or retaining member, and tongue-and-groove means circumscribing said block around its side and end faces and disposed between said recesses and said front face, the opposite side face having a groove therein disposed adjacent to and parallel with said rear face.

7. A tile for furnace construction, comprising a refractory block substantially parallelepiped in form and having oppositely disposed front and rear faces, oppositely disposed side faces, and oppositely disposed end faces, one of said side faces having a plurality of recesses therein communicating with said rear face and arranged in spaced formation extending substantially parallel with said rear face, the end recesses of such formation communicating respectively with said end faces, each of said recesses communicating with a groove spaced from said rear face, said groove being capable of interlocking cooperation with a supporting or retaining member, and tongue-and-groove means circumscribing said block around its side and end faces and disposed between said recesses and said front face, said tongue-and-groove means comprising a groove in one of said side faces and a tongue upon the opposite side face, and a groove in one of the end faces and a tongue upon the opposite end face.

8. A tile for furnace construction, comprising a refractory block substantially parallelepiped in form and having oppositely disposed front and rear faces, oppositely disposed side faces, and oppositely disposed end faces, one of said side faces having a plurality of recesses therein communicating with said rear face and arranged in spaced formation extending substantially parallel with said rear face, the end recesses of such formation communicating respectively with said end faces, each of said recesses communicating with a groove spaced from said rear face, said groove being capable of interlocking cooperation with a supporting or retaining member, and tongue-and-groove means circumscribing said block around its side and end faces and disposed between said recesses and said front face, said tongue-and-groove means comprising a groove in one of said side faces and a tongue upon the opposite side face, and a groove in one of the end faces and a tongue upon the opposite end face, and the opposite side face having a groove therein traversing it and disposed adjacent to and parallel with said rear face.

9. A tile for furnace construction, comprising a refractory block substantially parallelepiped in form and having oppositely disposed front and rear faces, oppositely disposed side faces, and oppositely disposed end faces, one of said side faces having three recesses therein communicating with said rear face, one of said recesses being centrally disposed with respect to the others, and said other recesses communicating respectively with said end faces, each of said recesses communicating with a groove spaced from said rear face, and the opposite side face having a longitudinally extending groove therein, said grooves being capable of interlocking cooperation with supporting or retaining members.

LOUIS H. HOSBEIN.
